UNITED STATES PATENT OFFICE.

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN.

PROCESS OF EXTRACTING BROMIN FROM BRINE.

1,323,173.

Specification of Letters Patent. Patented Nov. 25, 1919.

Application filed April 24, 1916, Serial No. 93,313. Renewed April 17, 1919. Serial No. 290,901.

To all whom it may concern:

Be it known that I, HERBERT H. Dow, a citizen of the United States, and a resident of Midland, county of Midland, State of Michigan, have invented a new and useful Improvement in Processes of Extracting Bromin from Brine, of which the following is a specification, the principle of the invention being herein explained and the best mode in which I have contemplated applying that principle, so as to distinguish it from other inventions.

The present improved process and apparatus for carrying on the same, relating as indicated to the extraction of bromin from brine, have regard more particularly to certain improvements in the general process described and claimed in U. S. Letters Patent No. 714,160, issued to me November 25, 1902. In dealing with natural brines, such as those herein involved, it must be remembered that there is only a trace of bromin present in the form of bromid, and that to take all of this out in practice, without at the same time taking out a large amount of chlorin, which is present in the form of chlorid in very much larger quantities, is a matter of no small difficulty. The object of the present invention is to provide for the systematic removal of all the bromin from such a brine, with the incidental extraction of the least possible amount of chlorin, such chlorin as is freed being utilized as an oxidizing agent so as to assist in liberating the bromin.

To the accomplishment of the foregoing and related ends, the invention, then, consists of the means and steps hereinafter described and particularly pointed out in the claims.

The annexed drawing and the following description set forth in detail one mode of carrying out the invention, such disclosed mode, however, constituting but one of various ways in which the principle of the invention may be used.

In said annexed drawing, the single figure there appearing represents diagrammatically a form of apparatus suitable for use in carrying out the present improved process.

The aforesaid apparatus, as well as the process exemplified in its operation, in reality more closely resemble the apparatus and process forming the subject-matter of U. S.

patent to A. E. Schaefer, for methods of extracting bromin, dated June 27, 1916, No. 1,188,838, than the original Patent No. 714,160 referred to above. By means, however, of the further changes herein made in such original apparatus, I am enabled to accomplish the desirable result, of systematically over-oxidizing the brine without the accumulation of an excess of chlorin in the apparatus, which will occur in the process as modified by said Schaefer. In other words, while I propose to over-oxidize the brine systematically, I simultaneously carry on a reduction step in a purifying tower located at a suitable point in the system, so that the net result is under-oxidation and the formation of surplus chlorin is thus avoided. In the other process just mentioned, on the contrary, the excess of free chlorin used in preliminarily oxidizing the fresh brine depletes the latter of bromid more and more until the original under-oxidation step becomes in reality an over-oxidation, and so much chlorin accumulates in the main system that the purifiers therein are unable to eliminate it.

The present apparatus, as in the case of such prior patents comprises a main system with a brine reservoir A from which the other parts of such system are supplied, and the auxiliary system likewise has a brine reservoir B from which the parts of such system are supplied, as also the reservoir of the main system.

Referring, first of all, to what has been styled the main system of the apparatus, the brine for the reservoir A is preliminarily treated in a tower B³, which constitutes in effect part of the auxiliary system. In other words, the brine from the tank B, constituting the primary source of supply, as it passes down through such tower, comes into contact with an ascending stream of air carrying free bromin and some chlorin, so that such brine is enriched by bromin, and any ferrous salts, or like impurities, are oxidized before the first oxidation step proper.

The brine from the reservoir A is first conducted to an oxidizer A¹, where oxidation may be accomplished in any approved fashion, as by one of the various means explained in U. S. Letters Patent *re* No. 11,232. Thence the brine flows into a blowout tower A² of familiar construction. The oxidation

step carried on in the aforesaid oxidizer is regulated so as to under-oxidize the brine, that is, free less than the total content of bromin. Accordingly, the gas recovered 5 from the blowout tower will be fairly free from chlorin, especially as the air therein used is that which has been preliminarily passed through tower B³.

From the blowout tower A², the residual 10 brine is conducted to a second oxidizer B¹, forming part of the auxiliary system, where its further treatment will be presently explained.

The air carrying the bromin blown out of 15 tower A² is next passed through a bromin-fed purifier A³, of familiar construction, which serves to eliminate any traces of chlorin, and thence passes over into an absorbing tower A⁵, where a reducing agent 20 such as iron, or other material capable of absorbing the bromin, is utilized in the formation of the final product, which will be ferric bromid in case such iron is used.

The oxidation step in the auxiliary system 25 is carried much further than the first described oxidation step in the main system, so as not only to free all the bromin contained in the brine therein being treated, but more or less chlorin in addition thereto. 30 The brine, with its content of these gases in solution, then passes through a blowout tower B² to waste, the gases blown out being conducted to a purifying tower B⁴, preferably bromid-fed, although a reducing agent, 35 that preferentially reacts with chlorin, may be employed therein, this tower being designed to remove substantially all of the chlorin produced by the over-oxidation in the preceding oxidation step. The air with 40 its bromin content, however, is carried on to tower B³, where the brine is treated preliminarily to such first or under-oxidation step, as has already been described.

The present process not only presents all 45 of the advantages over that of Patent No. 714,160 which the Schaefer process attains, but in addition, by the interposition of the purifying step following the over-oxidation of the brine in the auxiliary system, such 50 present process practically eliminates chlorin from the remaining steps of the process, and in particular prevents any accumulation of this element, which otherwise would prevent, in time, the operation of the process at 55 all. As a result of the foregoing, the gas blown out of tower A² in the main system includes practically nothing but bromin, so that a single purification step suffices, and this stage of the operation is correspondingly shortened. Moreover, it is of course, 60 unnecessary, with the foregoing arrangement, to accurately gage the amount of the over-oxidation, as has been in practice necessary heretofore in order to avoid the 65 accumulation of excess chlorin, so that the

present process really provides, for the first time, for the practical use of an over-oxidizing step in a system of this sort.

In other words, the sum of the two oxidation steps, in practice, has heretofore had to 70 be actually less than the content of bromin and reducing agents in the brine, otherwise chlorin was bound to occur in increasing quantities first in the secondary system and then there will not be sufficient bromin enrichment of the brine fed to the primary system to prevent over-oxidation in this system, so that as a result chlorin will develop in increasing amounts in this system also; whereas, by the present process, the total 80 oxidation may be excessive and yet the net result is automatically balanced to equal such bromin reducing agent content, thus insuring thorough extraction of the bromin, and, at the same time, giving an unusually 85 pure product, uncontaminated with chlorid.

Other modes of applying the principle of my invention may be employed instead of the one explained, change being made as regards the process herein disclosed, provided the step or steps stated by any one of the following claims or the equivalent of such stated step or steps be employed.

I therefore particularly point out and distinctly claim as my invention:—

1. The process of extracting bromin from bromid-containing brine, which consists in systematically over-oxidizing such brine and reducing the products of such oxidation at one stage in the process so that the net result of such oxidation is substantially equal to the bromin content.

2. The process of extracting bromin from brine containing bromid, which consists in systematically over-oxidizing such brine whereby chlorin as well as bromin is freed, and then eliminating such chlorin by the use of bromid so that the net result of such oxidation is substantially equal to the bromin content.

3. In a process of extracting bromin from bromid-containing brine, the steps which consist in oxidizing such brine short of its bromin content; thereupon oxidizing such brine in excess of its bromin content; blowing out the bromin and chlorin liberated in such over-oxidation step; substantially eliminating the chlorin from the gases thus blown out; and blowing out the bromin liberated in such under-oxidation step with the gas from the last-named step.

4. In a process of extracting bromin from bromid-containing brine, the steps which consist in oxidizing such brine short of its bromin content; thereupon oxidizing such brine in excess of its bromin content; blowing out the bromin and chlorin liberated in such over-oxidation step; substantially eliminating the chlorin from the gases thus blown out; oxidizing the brine preliminarily

to such under-oxidation step by treating with the bromin-containing gas from the last-named step; and then blowing out the bromin liberated in such under-oxidation 5 step.

5. In a process of extracting bromin from bromid-containing brine, the steps which consist in oxidizing such brine short of its bromin content; thereupon oxidizing such 10 brine in excess of its bromin content; blowing out the bromin and chlorin liberated in such over-oxidation step; substantially eliminating the chlorin from the gases thus blown out by purifying the latter with a 15 material preferentially reacting with such chlorin; and blowing out the bromin liberated in such under-oxidation step with the gas from the last-named step.

6. In a process of extracting bromin from bromid-containing brine, the steps which consist in oxidizing such brine short of its bromin content; thereupon oxidizing such brine in excess of its bromin content; blowing out the bromin and chlorin liberated in 25 such over-oxidation step; substantially eliminating the chlorin from the gases thus blown out by purifying the latter with a bromid; oxidizing the brine preliminarily to such under-oxidation step by treating with the 30 bromin-containing gas from the last-named step; and then blowing out the bromin liberated in such under-oxidation step with the residual gas.

7. In a process of extracting bromin from 35 brine containing bromid, the steps which consist in passing a current of air through such brine after having been oxidized in excess of its bromin content; substantially eliminating the chlorin from the gases thus blown out; then passing such air through 40 such brine in its original state to effect its preliminary oxidation and increase its bromin content; finally passing such air through the brine after it has been oxidized 45 short of its bromin content.

8. In a process of extracting bromin from brine containing bromid, the steps which consist in oxidizing such brine short of its bromin content; then oxidizing it in excess 50 of such content; passing a current of air in succession through such brine in its second and first stages of oxidation in the order

named; and substantially eliminating the chlorin from such air between such stages.

9. In a process of extracting bromin from 55 brine containing bromid, the steps which consist in preliminarily oxidizing such brine; next oxidizing it short of its bromin content; then oxidizing it in excess of such content; passing a current of air in succession through such brine in its third, first, and second stages of oxidation in the order named; and substantially eliminating the chlorin from such air between such third and first stages. 60

10. In a process of extracting bromin from brine containing bromid, the steps which consist in preliminarily oxidizing such brine; next oxidizing it short of its bromin content; then oxidizing it in excess of such 70 content; passing a current of air in succession through such brine in its third, first, and second stages of oxidation in the order named; and purifying such air between such third and first stages with a material preferentially reacting with chlorin, whereby the 75 latter is substantially eliminated.

11. In a process of extracting bromin from brine containing bromid, the steps which consist in preliminarily oxidizing such 80 brine; next oxidizing it short of its bromin content; then oxidizing it in excess of such content; passing a current of air in succession through such brine in its third, first and second stages of oxidation in the order 85 named; and purifying such air between such third and first stages with a bromid, whereby the chlorin in such air is substantially eliminated.

12. In a process of extracting bromin from 90 brine containing bromid, the steps which consist in preliminarily oxidizing such brine with purified bromin-laden air; next oxidizing it short of its bromin content with an oxidizing agent other than bromin; and 95 then oxidizing it in excess of such content, likewise with an oxidizing agent other than bromin.

Signed by me this 14th day of April, 1916.

HERBERT H. DOW.
